ATTYS.

UNITED STATES PATENT OFFICE.

NELLIE E. EWART, OF ARLINGTON, MASSACHUSETTS.

PORTABLE DRYING APPARATUS.

1,267,524.

Specification of Letters Patent. Patented May 28, 1918.

Application filed August 21, 1917. Serial No. 187,450.

To all whom it may concern:

Be it known that I, NELLIE E. EWART, a citizen of the United States, residing at Arlington, in the county of Middlesex and State of Massachusetts, have invented new and useful Improvements in Portable Drying Apparatus, of which the following is a specification.

This invention has for its object to provide a portable drying apparatus for household use, adapted to be inserted in the oven of a stove or range, and to hold a plurality of trays, charged with fruit or other food, in position to permit the hot air in the oven to have free access to the charges and cause the evaporation of moisture from said charges, and to permit a practically unobstructed escape of the evaporated moisture from the charges.

The invention consists in the improvements which I will now proceed to describe and claim.

Of the accompanying drawings forming a part of this specification,—

Figure 1 is a perspective view of the skeleton frame of my improved apparatus.

Fig. 2 is a perspective view of one of the trays.

Fig. 3 is a section on line 3—3 of Fig. 2.

Fig. 4 is a fragmentary sectional view showing a portion of the frame and portions of two of the trays.

The same reference characters indicate the same parts in all the figures.

My improved drying apparatus comprises a skeleton frame, including openwork frame ends adapted to horizontally support a plurality of shallow trays having foraminous bottoms. Each tray may include a rectangular sheet metal curb 12 and a woven wire bottom 13.

The openwork frame ends are formed to support the trays spaced from each other and to permit a practically unobstructed escape of vapor from the trays through said frame ends. Each frame end is composed of two upright members or standards 14, and a plurality of horizontal members 15 extending between and riveted or otherwise attached to the standards, said horizontal members being formed as runs adapted to guide and support the trays. The members 14 and 15 may be formed by sheet metal strips riveted together at 20, as shown by Figs. 1 and 4.

The standards 14 form opposite ends of

tray-receiving openings at opposite sides of the frame, and these sides may be termed the front and rear sides. The members or runs 15 project into said openings, so that the trays may be inserted in the openings and moved along the runs to their operative positions within the frame. The frame ends are connected by frame members 16, forming opposite sides of bottom and top openings in the frame. The members 14 and 16 may be parts of a single strip bent into rectangular form and suitably united at its ends. Two substantially rectangular parallel frame elements are therefore provided, each composed of two upright members or standards 14, and two horizontal members 16, one of said elements forming an open front portion and the other an open rear portion. The lower members 16 form feet adapted to rest on an oven bottom, and the upper members 16 form opposite sides of an open frame top. Said rectangular elements are connected and maintained spaced apart from each other by the runs 15. When the trays charged with material to be dried are in their operative positions, the apparatus as a whole may be inserted in an oven and supported by the bottom of the latter. The hot air in the oven has free access to the charges through the foraminous bottoms of the trays, the openwork frame ends, the front and rear side openings, and the bottom and top openings of the frame. A practically unobstructed escape of the moisture evaporated from the charges is permitted through the openwork frame ends, the front and rear openings, and the top opening of the frame. The oven door should be left ajar to permit the escape of the evaporated moisture from the oven.

The horizontal members 16 of said frame elements may be connected by transverse members 18, the upper one of which may constitute a handle.

It will be seen that the skeleton frame has spaced apart feet formed by the horizontal bottom portions of the rectangular frame elements, grid-shaped ends formed by the upright portions of said elements and the tray runs, and an open top formed by the horizontal top portions of the rectangular frame elements. This construction permits heat to rise freely from the exposed portion of an oven bottom on which the said feet rest, and through the grid-shaped ends and the open top.

I claim:

A portable drying apparatus comprising two substantially rectangular frame elements, formed of metal strips bent and united to form upright end portions and horizontal top and bottom portions, said elements constituting an open front and an open rear of a skeleton frame in which trays may be inserted, horizontal tray runs attached to said upright portions and connecting the rectangular elements in spaced relation, said runs projecting into the front

and rear openings bounded by said frame elements, and a plurality of trays movable through said openings and supported by 15 said runs, said skeleton frame having spaced apart feet, formed by said horizontal bottom portions and adapted to rest on an oven bottom, grid-shaped ends formed by said upright portions and tray runs, and an open 20 top formed by said horizontal top portions.

In testimony whereof I have affixed my signature.

NELLIE E. EWART.
